UNITED STATES PATENT OFFICE

WALTER LINDLEY, OF STOKE-ON-TRENT, ENGLAND, ASSIGNOR TO HERMAN C. KUPPER,
INC., OF NEW YORK, N. Y., A CORPORATION OF NEW YORK

DESIGN FOR A COVERED DISH OR SIMILAR ARTICLE

Application filed July 6, 1931. Serial No. 40,417. Term of patent 7 years.

To all whom it may concern:

Be it known that I, WALTER LINDLEY, a subject of the King of Great Britain, residing at Stoke-on-Trent, county of Stafford, England, have invented a new, original, and ornamental Design for a Covered Dish or Similar Article, of which the following is a specification, reference being had to the accompanying drawings, forming part thereof.

I claim:

The ornamental design for a covered dish or similar article, as shown.

WALTER LINDLEY.
